(No Model.)

A. H. JOHNSON.
SWITCH AND LOCK MOVEMENT.

No. 518,721.

Patented Apr. 24, 1894.

UNITED STATES PATENT OFFICE.

ARTHUR H. JOHNSON, OF RAHWAY, NEW JERSEY.

SWITCH AND LOCK MOVEMENT.

SPECIFICATION forming part of Letters Patent No. 518,721, dated April 24, 1894.

Application filed May 23, 1893. Serial No. 475,202. (No model.)

To all whom it may concern:

Be it known that I, ARTHUR H. JOHNSON, of Rahway, in the county of Union and State of New Jersey, have invented a new and useful Improvement in Switch and Lock Movements, of which the following is a specification.

My invention relates to an improvement in switch and lock movements in which the locking device for engaging the front rod and holding it in position is under the immediate control of an arm of the switch operating lever.

A practical embodiment of my invention is represented in the accompanying drawings, in which—

Figure 1 is a plan view of the switch operating and locking mechanism and a portion of one of the rails of a main and shunt track in connection with which the switch and locking mechanism is employed. Fig. 2 is an edge view of the same. Fig. 3 is a top plan view of a modified structure, and Fig. 4 is a top plan view of still another modified structure.

The base plate upon which the movable parts are mounted is denoted by A and conveniently consists of an oblong rectangular plate, in practice sufficiently long to rest upon the projected ends of three consecutive rail-way ties or sleepers, as indicated in Fig. 1. A bar a is secured at its opposite ends to raised portions a' on the plate A so as to leave a space between it and the plate A for securing the rocking parts in position.

It is obvious that overhanging lips or lugs of ordinary structure might be cast integral with the plate A or secured thereto in place of the bar a, but I prefer the latter structure because it leaves a free space intermediate of its ends for the rocking movement of the levers hereinafter to be described, whether they be three-armed—as shown—or whether they be four-armed—as is sometimes found desirable in order to change the direction of the operating rod.

Between the plate A and the bar a, the switch and detector bar and operating lever B is pivoted, its pivot having a bearing at one end in the plate and at the opposite end in the bar a. The lever B is here shown as a three-armed lever, one of these arms b having connected to its end the operating rod C;

an oppositely extending arm b' having a connection with the alligator jaws on the end of the lever D; the opposite end of which is connected with the switch operating rod E; and the third arm b² extending at an angle to the arms b and b', having connected to its end a rod f for operating the detector bar F.

The front rod G which is connected to the switch rails H so as to be moved by the movement of the switch rails under the action of the switch operating rod E, extends transversely across the plate A, underneath the same, and is provided at suitable intervals on its upper side with abutments g and g', the free ends of which are spaced from the body of the rod G sufficient to receive the edges of the plate A between them and the rod so that as the front rod G is slid back and forth with the movement of the switch rails, the one or the other of the abutments g, g' will be slid into position over the edge of the upper face of the plate A. g is shown in such position in Fig. 1.

On the upper face of the plate A there is formed a raised track I having the curve of an arc of a circumference, and on said track there is seated a locking device K having in its under face a groove k corresponding to the raised track I and adapted to receive the track with an easy sliding fit. The locking device K, preferably of curved form, as shown, and of sufficient length so that the movement of the lever B for operating the switch will be sufficient to throw one end or the other of the locking device across the path of the abutments g, g' on the front rod. The locking device K is provided on its upper face and preferably at its center portion, as shown, with a pair of uprising lugs k' between which the arm b of the lever B is adapted to fit so that as the arm b is moved, the locking device K will be slid along the track.

As represented in Fig. 1, the lever B has been rocked in the direction to draw the switch rail H against the main rail H' and to throw the front rod G outwardly with its abutment g over the edge of the plate A. This movement of the lever B by means of its arm b engaged with the locking device K, has slid the latter along the track I so as to bring the end

of the locking device in front of the abutment g' , between it and lugs L uprising from the plate A. Such position of the locking device will effectually lock the front rod G in position to hold the points of the switch rail in close contact with the main rail and, because of the action of the detector bar F, it will be impossible to operate the switch to release the locking device from the front bar so long as the train is passing.

To throw the switch rails away from the main rails, the lever B is rocked in the opposite direction, the first part of its movement withdrawing the locking device K from in front of the abutment g' , while its arm b' moves along the face of one of the alligator-jaws without affecting the lever D, then rocking the lever D to operate the switch and at the same time sliding the front rod G in a direction toward the track and finally, while the end of the arm b' moves along the opposite alligator-jaw sliding the locking device K in front of the abutment g —between it and the lugs on the plate A—to lock the front rod and hence the switch rails in the open position.

In the form represented in Fig. 3, the locking device K' is fixed to the arm b of the operating lever and in place of the lugs L, uprising from the plate A, the ends of the locking device are supported by radial braces k^2 .

In the form shown in Fig. 4, the locking device K^2 is made to travel in a straight line along a slot a^2 in the plate A, the said locking device being provided with depending lugs k^3 at or near its opposite ends which, when the lever is thrown in one direction or the other engage the notches g^2 in the upper face of the front rod G to lock it in position. In this instance the stud b^3 which connects the arm b of the lever with the locking device is permitted a sliding movement transversely across the locking device K^2 in a channel k^4 provided for the purpose, in order to account for

the curved path of the stud b^3 in its movement with the arm b .

It is obvious that other slight changes than those referred to might be made in the form and arrangement of the several parts without departing from the spirit and scope of my invention. Hence I do not wish to limit myself strictly to the structure and arrangement of parts herein shown and described, but

What I claim is—

1. In combination, a switch operating rod, a detector bar, a multiple armed operating lever for moving the switch operating rod and detector bar, a sliding locking device engaged with an arm of the operating lever and abutments on the front rod with which the sliding locking device is adapted to engage as the operating lever is rocked, substantially as set forth.

2. In combination, a switch operating rod, a front rod, an operating lever for imparting motion to the switch rod, a curved track and a locking device mounted to slide on the curved track into and out of locking engagement with the front rod, the said locking device being under the control of the operating lever to throw it into and out of locking position, substantially as set forth.

3. The combination with a base plate and a bar spaced therefrom and secured thereto, of switch operating jaws and a lever pivotally secured between the base plate and bar, an operating lever pivotally secured between the base plate and bar in position to engage the switch operating jaws, a switch operating rod, a front rod and a locking device under the control of the said operating lever to lock the front rod, substantially as set forth.

ARTHUR H. JOHNSON.
